UNITED STATES PATENT OFFICE.

JAMES H. DAVIS, OF CLAIRTON, PENNSYLVANIA.

CAR-DOOR-LOCKING MECHANISM.

Application filed October 25, 1922. Serial No. 596,843.

To all whom it may concern:

Be it known that I, JAMES H. DAVIS, a citizen of the United States, and a resident of Clairton, in the county of Allegheny and

5 State of Pennsylvania, have invented certain new and useful Improvements in Car-Door-Locking Mechanisms, of which the following is a specification.

This invention relates to railway cars 10 and more particularly to coke quenching cars adapted to receive the hot coke from coke ovens, and has for its object the provision of a novel door locking mechanism adapted to prevent the opening of the discharge doors on the car, except at pre-determined points.

Another object is to provide a car of the class described having the novel construction and combination of parts described in 20 the following specification and illustrated in the accompanying drawings, in which:

Figure 1 is a side elevation of one-half of a car embodying this invention, partly broken away for clearness.

25 Figure 2 is a top plan thereof.

Figure 3 is an end elevation of the car, broken away to show the door operating mechanism.

Figure 4 is a sectional elevation, taken 30 on the line IV—IV of Figure 1, showing the novel locking mechanism in elevation.

Referring more particularly to the drawings, the numeral 2 designates the body of the car as a whole, which is supported on 35 trucks 3 and is composed of an inclined floor or bottom 4, end walls 5 and side wall 6, in which are doors 7 through which the material is discharged from the car.

The doors 7 are adapted to be opened and 40 closed, and also held in their respective positions, by a door operating mechanism composed of links 8 which have one end pivotally secured to said doors and their other end pivotally secured to one end, of arms 9 secured on a shaft 10 which is provided with 45 a gear 11 in mesh with an operating rack member 12 secured to the piston 13 of a fluid operated cylinder 14. The cylinder 14 is a two way cylinder having fluid supply pipes 50 15 entering each end thereof, and is controlled by the operator through valves (not shown).

The links 8 have their rear ends, which 55 are pivotally connected to the arms 9, curved or bent downwardly so that when the doors 7 are fully opened or closed the pivot point

connecting the links 8 and arms 9 will lie in a plane below the longitudinal axis of the shaft 10, thus forming a lock to hold the doors in either extreme.

60

In order to lock the doors 7 when not fully closed and to prevent the accidental opening of the doors 7 from any position, either due to the carelessness of the operator or to causes beyond his control, such as 65 leaky valves, etc., the novel locking mechanism of this invention is provided.

This mechanism comprises a ratchet wheel 17 secured on the shaft 10, a rocking lever or dog 18 pivoted intermediate its ends on 70 a bracket 19 mounted on cross beams 20 secured to the under frame of the car, and an operating lever 21 suspended from one end of the lever 18 and mounted to reciprocate in guide yokes 22 on the cross beams 20. 75

The lever 21 has its lower end bifurcated forming a clevis 23 in which is mounted a roller 24 adapted to engage and ride along a raised or cam rail 25 which has its ends inclined to form approaches 26.

80

The operation of this novel door locking mechanism is as follows—The normal weight of the lever 21 and roller 24 is sufficient to normally pull the rear end of the lever or dog 18 downwardly so that its 85 forward end projects upwardly into engagement with the ratchet wheel 17, and thus prevents the rotation of the shaft 10 regardless of the power applied to the cylinder 14. As the car approaches the coke wharf or 90 other desired discharge station the roller 24 will ride up on the rail 25 located between the track rails at this point, thus causing the lever 21 to move upwardly and rock the lever or dog 18 away from the ratchet 17 95 and thereby release the shaft 10 so that it may be readily rotated by the cylinder 14.

The advantages of locking the discharge doors of a coke quenching car will be readily appreciated by those skilled in the art. 100 The accidental discharge of coke along the track or at the quenching racks is prevented, the discharge of hot coke and its accompanying dangers is prevented, and as a whole the operation of the quenching car is 105 facilitated and made safer.

I claim:—

1. In a railway car having discharge doors hinged along one of their sides, the combination with door operating mechanism 110 including a shaft adapted to be rotated to open said doors, and means for rotating

said shaft, of means for locking said shaft against rotation, and means located at a predetermined point in the path of travel of said car for automatically tripping said locking means to release said shaft.

2. In a railway car having discharge doors hinged along one of their sides, the combination with door operating mechanism including a shaft adapted to be rotated to open said doors, and means for rotating said shaft, of means for locking said shaft against rotation, and means located at a predetermined point in the path of travel of said car adapted to trip said locking means to thereby release said shaft.

3. In a railway car having discharge doors hinged along one of their sides, the combination with door operating mechanism including a shaft adapted to be rotated to open said doors, and means for rotating said shaft, of a ratchet on said shaft, a dog adapted to engage said ratchet to

lock said shaft against rotation, means for normally holding said dog in engagement with said ratchet, and means located at a predetermined point in the path of travel of said car adapted to trip said last named means to thereby release said dog from said ratchet and permit said shaft to be rotated.

4. The combination with a railway car having a swinging discharge door on its one side, and door operating mechanism adapted to positively open and close said door, said mechanism being adapted to lock said door only when said door is fully closed, of a second locking means adapted to lock said door against movement regardless of its position, and means located at a predetermined point in the path of travel of said car adapted to trip said last named locking means.

In testimony whereof, I have hereunto set my hand.

JAMES H. DAVIS.
